UNITED STATES PATENT OFFICE.

SAMUEL H. RICE, OF SAN FRANCISCO, CALIFORNIA, ASSIGNOR TO KALAMAZOO LOOSE LEAF BINDER CO., OF KALAMAZOO, MICHIGAN.

CABINET AND RECORD APPLIANCE.

1,288,681.

Specification of Letters Patent. Patented Dec. 24, 1918.

Application filed June 15, 1917. Serial No. 174,918.

To all whom it may concern:

Be it known that I, SAMUEL H. RICE, a citizen of the United States, residing at San Francisco, California, have invented certain new and useful Improvements in Cabinets and Record Appliances, of which the following is a specification.

This invention relates to improvements in cabinets and record appliances.

10 My improvements relate particularly to means for filing and handling record sheets and loose leaf binders therefor, although the same may be readily adapted for handling bound record books.

15 The main objects of this invention are:

First, to provide an improved cabinet for record books in which several record books may be manipulated and all are conveniently and readily accessible and at the same time 20 provide a structure which is quite compact and simple.

Second, to provide an improved appliance for the handling of loose leaf binders and the sheets thereof which greatly facilitates 25 their manipulation.

Third, to provide an appliance having these advantages which is simple and economical and very convenient to use.

Further objects, and objects relating to 30 structural details, will definitely appear from the detailed description to follow.

I accomplish the objects of my invention by the devices and means described in the following specification. The invention is 35 clearly defined and pointed out in the claims.

A structure which is a preferred embodiment of my invention is clearly illustrated in the accompanying drawing, forming a part of this specification, in which:

40 Figure I is a detail perspective view of a structure embodying the features of my invention with the cover opened, two of the binder holders being shown in their elevated and open position with binders therein, the 45 third holder being shown in its elevated position without a binder therein, parts of the cabinet being broken away to show structural details.

Fig. II is an enlarged detail transverse 50 section on a line corresponding to the broken line 2—2 of Fig. I.

Fig. III is a perspective view of one of the holder members in its collapsed position.

Fig. IV is a detail perspective view of one

of the holders showing structural details 55 thereof, the supplementary or center member being shown in disengaged position by dotted lines.

Fig. V is an end view of one of my improved holders in collapsed position with 60 the binder therein, the adaptability to binders of different sizes being indicated by dotted lines.

Fig. VI is a perspective view of a slightly modified form of my improved holder in its 65 extended position.

In the drawings, similar reference characters refer to similar parts throughout the several views and the sectional views are taken looking in the direction of the little 70 arrows at the ends of the section lines.

Referring to the drawings, the cabinet illustrated comprises a frame consisting of top and bottom longitudinal rails 1 and 2, end cross pieces 3, and suitable wall panels 75 4. The top rails have grooves 5 in their inner edges adapted to receive the flexible roll top 6. The details of this roll top are not illustrated as suitable roll or flexible tops are known.

80 In the structure illustrated, the corner posts 7 are extended to provide legs 8. I provide a plurality of holders which in the structure illustrated comprise the rectangular frame-like bases 9 and a pair of holder 85 members designated generally by the numerals 10 and 11. These holder members are pivoted at 12 to the end members of the base. The holder members comprise sides 13 and 14 and ends 15 and 16 secured there- 90 to so that the members may be tilted or adjusted to an outwardly inclined relation to provide a pair of supports, each adapted to receive a binder member, as illustrated in Fig. I. The end members are of such width 95 that they may be collapsed, as shown to permit the holder being adjusted to an upright position to support the binder in closed position.

100 The end members are provided with slots 17 adapted to receive the binder strips of a binder such as shown in the patent to Wiggin, No. 1,1784,458, March 7, 1916, the structure illustrated being particularly adapted for use with loose sheet binders of 105 this type. It is, however, readily adapted and desirable for use with various other types of binders.

I provide a removable center or supplemental member 18, A-shaped to coact with the end members, filling the gap between the same when they are adjusted to their extended position. This holder illustrated is the same as that illustrated and made the subject matter of the claims of my copending application Serial No. 174,919, filed June 15, 1917, and, therefore, is not described in further detail herein.

In the embodiment shown in Figs. V and VI, the center member 18, is adapted to overlap the end member 15 instead of end abutting the same, as shown in Fig. IV. This is also described in detail in my said copending application and I do not, therefore, describe the same in further detail herein.

The cabinet is provided with a plurality of opposed vertical ways 20 adapted to guide the carrier bars 21 of the holders, the holders being provided with spaced plates 22 embracing these bars. These carriers are suspended by cables 23 which are secured to the ends of the carrier bars and passed over guide pulleys 24 arranged between the spaced longitudinal members 25, see Fig. III. Counterweights 26 are secured to the opposite ends of these cables, the counterweights being in the form of bars having a plurality of removable plates 27 so that the counterweight may be adjusted to approximately the load in the holder.

With the parts thus arranged, the binders with their sheets may be arranged in the holders, the holders closed or collapsed and lowered into the cabinet. When access is desired to any binder, the same is raised, and the holder opened and the binder extended and adjusted therein, as shown in Fig. I, in which position the sheets are readily accessible and convenient for manipulation.

The supplemental end members 18 are preferably provided with guides 28 for sheets so that they may be offset to indicate selected groups.

To facilitate the use of the appliances, I provide a table 29 adapted to receive a typewriter or accounting machine. This table is mounted upon a track 30 on the side of the cabinet so that it may be moved along to a convenient position relative to the particular binder in use. With this equipment, a large number of accounting sheets may be conveniently handled and are all readily accessible and further, the structure is quite compact and when closed the records are effectively protected.

The cabinet may be formed of metal or other material, as desired, for protection.

I have not attempted to illustrate or describe various modifications and adaptations which I contemplate and which might be desired in adapting my improvements to various uses for which it will be found advantageous, as I believe the disclosure made will

enable those skilled in the art to which my invention relates to embody or adapt the same as may be desired.

Having thus described my invention, what I claim as new and desire to secure by Letters Patent is:

1. In a structure of the class described, the combination of a cabinet open at the top and provided with a plurality of pairs of opposed vertical carrier guide ways, and a rolltop, holders each comprising a pair of members mounted for adjustment to provide a pair of supports each adapted to receive a binder member with sheets resting thereon or to be collapsed to support a closed binder in upright position, bar-like carriers on which said holders are mounted disposed in said ways, and suspending cables for said carriers provided with adjustable counterweights whereby said holders may be collapsed and lowered with binders therein into said cabinet or elevated through the top thereof and extended, for the purpose specified.

2. In a structure of the class described, the combination of a cabinet provided with a plurality of pairs of opposed vertical carrier guide ways, holders each comprising a pair of members mounted for adjustment to provide a pair of supports each adapted to receive a binder member with sheets resting thereon or to be collapsed to support a closed binder in upright position, bar-like carriers on which said holders are mounted disposed in said ways, and suspending cables for said carriers provided with adjustable counterweights whereby said holders may be collapsed and lowered with binders therein into said cabinet or elevated and extended, for the purpose specified.

3. In a structure of the class described, the combination of a cabinet provided with vertical guide ways, holders each comprising a pair of members mounted for adjustment to provide a pair of supports each adapted to receive a binder member with sheets resting thereon or to be collapsed to support a closed binder, carriers for said holders disposed in said ways, and suspending cables for said carriers provided with counterweights whereby said holders may be collapsed and lowered with binders therein into said cabinet or elevated and extended, for the purpose specified.

4. In a structure of the class described, the combination of an open topped cabinet provided with vertical guide ways, holder carriers mounted for vertical adjustment in said ways, holders mounted on said carriers and each comprising a pair of members adjustably associated so that when raised they may be adjusted to an open position above the plane of their collapsed position in the cabinet to provide a pair of supports to support a binder with the sheets resting thereon, or collapsed to support a closed binder.

5. In a structure of the class described, the combination of a cabinet provided with a vertical guide way, a holder comprising a pair of members mounted for adjustment to 40 provide a pair of supports each adapted to receive a binder member with sheets resting thereon or to be collapsed to support a closed binder, a carrier for said holder disposed in said way, and suspending cables for said carrier provided with adjustable counterweights whereby said holder may be collapsed and lowered with a binder therein into said cabinet or elevated through the top thereof and extended, for the purpose specified.
- 10 6. In a structure of the class described, the combination of a cabinet open at the top, and provided with a plurality of vertical guide ways, a holder adapted to be extended to 45 support a book in an open position or collapsed to support the book in a closed position, carriers on which said holders are mounted disposed in said ways, and suspending cables for said carriers provided with 50 counterweights whereby said holders with books therein may be collapsed and lowered into said cabinet or elevated through the top thereof and extended, for the purpose specified.
- 15 7. In a structure of the class described, the combination of a frame, a binder holder comprising side and end members pivotally mounted for adjustment to provide a pair of V-shaped supports each adapted to receive a binder member with sheets resting 55 thereon or to be swung to a collapsed position with the side members engaging the sides of a binder resting upon the end members, and means whereby said holder may be retracted into the said frame when collapsed or projected to operative position.
- 20 8. In a structure of the class described, the combination of a frame, a binder holder comprising side and end members pivotally mounted for adjustment to provide a pair of V-shaped supports each adapted to receive a binder member with sheets resting 60 thereon or to be swung to a collapsed position with the side members engaging the sides of a binder resting upon the end members, and means whereby said holder may be retracted into the said frame when collapsed or projected to operative position.
- 25 9. In a structure of the class described, the combination of a frame, a holder adapted to be elevated in said frame and extended into operative position or collapsed and lowered, and an adjustable counterbalance therefor, 65 all coacting for the purpose specified.
- 30 10. In a structure of the class described, the combination of a frame, and a series of holders disposed side by side, said holders being adapted to be elevated through the top of the frame and extended to support a book in open position or collapsed and lowered to support a book in closed position, the holders being arranged to overlap adjacent lower 70 holders when extended.
- 35 In witness whereof, I have hereunto set my hand and seal in the presence of two witnesses.
